FRONT HOUSING FOR WINDOW AIR CONDITIONING UNITS

Orville W. Farver, Tecumseh, Mich., assignor to Blissfield Manufacturing Company, Blissfield, Mich., a corporation of Michigan

Application July 6, 1954, Serial No. 31,289

Term of patent 14 years

(Cl. D62—4)

FIG. 1.

FIG. 2.

FIG. 3.

FIG. 4.

FIG. 5.

To all whom it may concern:

Be it known that I, Orville W. Farver, a citizen of the United States and resident of Tecumseh, in the county of Lenawee and State of Michigan, have invented a new, original, and ornamental Design for a Front Housing for Window Air Conditioning Units, of which the following is a specification, reference being had to the accompanying drawings, forming a part thereof.

In the drawings,

Fig. 1 is a perspective front view of a front housing for window air conditioning units showing my new design; Figs. 2 and 3 are opposite end views thereof;

Fig. 4 is a rear view thereof, and
Fig. 5 is a view similar to Fig. 1, with the compartment door open.

I claim:

The ornamental design for a front housing for window air conditioning units, substantially as shown.
